UNITED STATES PATENT OFFICE.

FREDERICK H. A. MOEHLLENBROCK, OF ST. LOUIS, MISSOURI.

TOBACCO-PIPE.

1,116,317.

Specification of Letters Patent.

Patented Nov. 3, 1914.

Application filed December 20, 1913. Serial No. 807,894.

To all whom it may concern:

Be it known that I, FREDERICK H. A. MOEHLLENBROCK, a citizen of the United States of America, residing in the city of St. Louis and State of Missouri, have invented certain new and useful Improvements in Tobacco-Pipes, of which the following is a specification.

The primary object of this invention is to provide improved means for separating the nicotine and liquids from the smoke.

Another object is to provide an improved removable nicotine and moisture collector.

A further object is to provide improved means adjacent the nicotine and moisture collector for preventing the return of moisture from the collector into the smoke ducts.

Other and further objects will appear in the specification and be specifically pointed out in the appended claims, reference being had to the accompanying drawings exemplifying the invention, and in which.

Figure 1 is a longitudinal section through a pipe showing this improved device applied thereto. Fig. 2 is a side elevation of the bowl of a pipe, and a portion of the stem, showing one of the cut-away portions of the bowl which provides means of access to the collector. Fig. 3 is an inverted sectional view taken on the line III—III, Fig. 1. Fig. 4 is an inverted sectional view taken on the line IV—IV, Fig. 1.

Referring by numerals to the accompanying drawings: 1 designates the body portion of a pipe, 2 the bowl, and 3 the base. Leading from the base is a stem 4. Secured to said stem by the nipple 5 is a mouthpiece 6. Formed in the base 3 is a recess 7, said recess being for the reception of a nicotine and liquid collector 8, said collector comprising a downwardly bent shell 9 and a removable cover 10. Formed on the top portion 11 of said shell 9 and depending therefrom is a funnel 12. Said shell 9 is held in place by the dents 13 which are made in the side walls of said shell after said shell has been inserted in the recess 7. These dents engage the side walls of said recess. Formed in the bottom of the bowl 2 is a central opening 14, said opening being threaded and adapted to receive the threaded end 15 of a removable hollow stem 16, said stem having its opposite end flared outwardly forming an inverted funnel, as shown at 17. Formed at the upper end of the recess 7, and at the center thereof, is a countersunk

opening 18, said opening 18 being in communication with the smoke duct 19 of the stem 4. Leading from said smoke duct is the smoke duct 20 of the mouthpiece 6. 60

When this improved pipe is in use, the products of combustion will pass down through the hollow stem 16 and will enter a collector 8. The smoke will then pass upwardly around the lower end of the hollow stem 16 and through the funnel 12 and into the countersunk opening 18. This countersunk opening 18 being in communication with the smoke duct 19 will allow the smoke to be introduced into the mouth of 70 the user. If any moisture is derived from the burning tobacco in the bowl 2, said moisture will also travel downwardly through the hollow stem 16 and into the collector 8. In the event of saliva traveling downwardly 75 through the smoke ducts 19 and 20, it will eventually be deposited in the collector through the funnel 12.

The flared end 17 of the hollow stem 16 will protect the inlet opening of the funnel 80 12 against particles that might have been deposited in the collector 8 in the event of the pipe receiving a sudden jar. If a pipe of this improved construction is laid on its side, or if turned upside down, the funnel 12 85 will prevent any of the substances that might be inside the collector from getting into the smoke ducts.

In cleaning this improved pipe, the cover 10 is engaged by placing the tips of the 90 fingers in the notches 21 which are formed on the sides of the pipe at the base, and the cover is removed from the shell 9. This cover will contain the refuse from smoking and can readily be cleaned out. If it is desired to clean the smoke ducts 19 and 20 by inserting a pipe cleaner therein, it is preferable to remove the hollow stem 16 which is done by engaging the flared end 17 and unscrewing said hollow stem. This will allow 100 any refuse that is in the aforesaid ducts to be pushed into the countersunk hole 18 from which it will fall through the funnel 12. The removable cover 10, when set into the recess 7 is flush with the base 3 of the pipe 105 so it will not give an unsightly appearance to said pipe.

What I claim is:

1. A pipe comprising a body portion, and a base portion, a bowl formed in said body 110 portion, a moisture collector having a depending funnel located therein formed in

said base portion, a removable cover for said collector, and a hollow stem leading from said bowl to said collector passing through said funnel.

5. 2. A pipe comprising a body portion, and a base portion, a bowl formed in said body portion, a moisture collector having a depending funnel located therein formed in said base portion, a removable cover for said collector, and a hollow stem leading from said bowl to said collector passing through said funnel, said hollow stem having a flared lower end.

15. 3. A pipe comprising a body portion, and a base portion, a bowl formed in said body portion, a moisture collector having a depending funnel located therein formed in said base portion, a removable cover for said collector, a hollow stem leading from said bowl to said collector passing through said funnel, said hollow stem having a flared lower end, and a smoke duct leading from said funnel.

25. 4. A pipe comprising a body portion, and a base portion, a bowl formed in said body portion, a moisture collector having a depending funnel located therein formed in said base portion, a removable cover for said collector, and a hollow stem leading from said bowl to said collector passing through said funnel, said hollow stem having a flared lower end.

end, said flared end being located below said funnel.

5. A pipe comprising a body portion, and a base portion, a bowl formed in said body portion, a moisture collector having a depending funnel located therein formed in said base portion, a removable cover for said collector, a hollow stem leading from said bowl to said collector passing through said funnel, said hollow stem having a flared ends, said flared end being located below said funnel, and a smoke duct leading from said funnel.

6. A pipe comprising a body portion, and a base portion, a bowl formed in said body portion, a recess formed in said base portion, a moisture collector located in said recess, said collector comprising a depending shell, and a removable cover adapted to engage said shell, a funnel depending from the top of said shell, a hollow stem leading from said bowl to said collector, one end of said stem being flared, said flared end being located below said funnel, said funnel communicating with said collector, and a smoke duct leading from said funnel.

FREDERICK H. A. MOEHLENBECK.

In the presence of—

M. C. HAMMON,
H. G. FLETCHER.
